THE NORRIS PETERS CO., PHOTO-LITHO., WASHINGTON, D. C.

UNITED STATES PATENT OFFICE.

ABRAHAM L. A. HIMMELWRIGHT, OF NEWARK, NEW JERSEY, ASSIGNOR TO THE NEW JERSEY WIRE CLOTH COMPANY, OF TRENTON, NEW JERSEY.

FIREPROOF CONSTRUCTION.

SPECIFICATION forming part of Letters Patent No. 644,912, dated March 6, 1900.

Application filed August 20, 1897. Serial No. 648,855. (No model.)

To all whom it may concern:

Be it known that I, ABRAHAM L. A. HIMMELWRIGHT, a citizen of the United States, residing at Newark, county of Essex, and State of New Jersey, have invented certain new and useful Improvements in Fireproof Constructions, fully described and represented in the following specification and the accompanying drawings, forming a part of the same.

10 The object of the present invention is to provide an improved fireproof floor construction, and especially an improved fireproof filling for use between iron or steel floor-beams for the purpose of preventing the progress and 15 spread of fires, as well as protecting, with a non-inflammable material, the floor-beams.

The main feature of the invention consists in an improved construction employing light iron or steel work between the floor-beams in 20 connection with metal lathing in such a manner as to dispense with the necessity of erecting temporary wood centering to support the concrete while green, as is now used in many other forms of fireproof filling employing concrete.

25 The invention consists in certain features of construction in a fireproof floor provided with light metal bars for supporting the concrete while green and strengthening the construction after the concrete has set and certain combinations of steel bars and other light metal fixtures, metal lathing, and concrete, together with an improved clamp for use in fireproof constructions, all as will be particularly described hereinafter and specifically pointed out in the claims.

30 As a full understanding of the invention can best be had by a detailed description of a construction embodying all the features of the same, such a description will now be given in connection with the accompanying drawings, illustrating a preferred form of fireproof floor construction, in which all the features of the invention are combined.

45 In the drawings, Figure 1 is a vertical section of the construction transverse to the floor-beams. Fig. 2 is a plan of the ironwork supported by the beams without the wire lathing and concrete. Fig. 3 is a section par-

allel with the floor-beams on the line 3 of 50 Fig. 2.

Referring to said drawings, A are the floor-beams, shown as the common I form, and B a flooring, of wood or other suitable material, supported by the tops of the beams and 55 wooden or similar studding C, which is preferably, but not necessarily, employed. Upon the lower flanges of these beams are supported flat steel or iron bars D, placed edge-wise vertically to secure as great strength for 60 the support of the concrete as possible with a light bar, and these bars are preferably formed with a half-turn at their extreme ends, as shown, to form horizontal portions which rest upon the flanges of the floor-beams. 65 The size of these bars D will vary with the spans between the floor-beams, but in each case are designed so as to have sufficient strength to sustain the weight of the concrete while green. The flat ends of the bars D may 70 simply rest upon the flanges of the beams; but preferably some means is used for the purpose of holding the bars firmly in position on the flanges. For this purpose any suitable form of clamp may be used; but I prefer- 75 ably use clamps E of the form shown, consisting of metal rods bent to form a loop 1, projecting above the flanges and through which the ends of the bars are passed, and legs 2, extended underneath the flanges, so 80 as to hold the bars firmly to the flanges of the beams. These bars D are tied together by spacers or supporters F, which are preferably solid steel rods bent to form loops 5, fitting over the tops of the bars D, these spac- 85 ers or supporters serving the double purpose of preventing the bars D from buckling side- 90 wise and increasing the rigidity and strength of the construction. The bars D, with the clamps E and spacers F, are placed in position, and then wire lathing G, provided with solid steel stiffening rods or bars 3 at suitable intervals, is applied to the under side of the beams A and bars D and supported from the bars, preferably by wire ties 4, as shown, 95 a flat lathing-surface thus being formed throughout the under side of the entire floor construction. Concrete H, mixed in suitable

95

proportions to give the necessary strength for any given requirements, is then filled in on top of the wire lathing G to the desired depth and preferably is packed around the webs 5 and top flanges of the floor-beams, as shown.

The space between the concrete and the flooring B, of wood or other material, may be left open to form an air-space, or it may be filled with ashes or other suitable light material I, as shown, and the flooring B then placed in position. The studding C is thus protected against fire by the filling I. If this filling is not used, but an air-space is left between the floor and concrete, I preferably pack the concrete in on both sides of the studding to the top of the latter in the same manner as shown in connection with the floor-beams.

The plaster ceiling K is applied to the lathing G in the usual manner from the under side.

It will be understood that my invention is not to be limited to the exact form or arrangement of parts in the construction shown, but 25 that many modifications may be made therein without departing from the invention. Thus a similar arrangement of the ironwork may be used with the concrete-supporting bars D resting on the top flanges of the floor-beams, clamps of suitable form being used to hold the bars in place or such clamps being omitted. Changes in the form of the concrete-supporting bars and the manner in which they are supported on the beams may 35 be made, and the spacers and clamps may readily be modified in form.

What I claim is—

1. A fireproof floor construction having light metal bars arranged edgewise vertically 40 and extending from floor-beam to floor-beam, metallic lathing supported by and below said bars and parallel with the lower edges of said bars to form a foundation to receive the con-

crete, and a body of concrete extending from floor-beam to floor-beam applied from above 45 on said lathing and in which the bars are embedded, said metal bars and lathing being constructed and arranged to support the concrete while the concrete is green and provide tension-bars for the construction, substantially as described.

2. The combination with floor-beams, of light metal bars arranged edgewise vertically and entirely supported by said beams and extending from beam to beam, metal spacers 55 connecting said bars longitudinally of the beams, and metallic lathing supported by and below said bars, all constructed and arranged to receive and support the body of concrete, substantially as shown and described.

3. The combination with the beams A, of the flat metal bars D placed edgewise vertically and bent at right angles at their ends to form horizontal portions resting upon the beams, metallic lathing supported by and below said bars, and concrete or similar plastic material filled in from above upon said metallic lathing and in which the metal bars are embedded substantially as shown and described.

4. The combination with the beams A, of bars extending from beam to beam and with their ends resting upon the flanges of the beams, and clamps E having loops 1 above the flanges of the beams, through which loops 75 the bars pass and legs 2 below the flanges of the beams, substantially as shown and described.

In testimony whereof I have hereunto set my hand in the presence of two subscribing 80 witnesses.

ABRAHAM L. A. HIMMELWRIGHT.
